CLAIM

The ornamental design for a cap for shaver blade, as shown and described.

DESCRIPTION

FIG. 1 is a perspective view of a cap for shaver blade, showing my new design;

FIG. 2 is a front elevational view thereof;

FIG. 3 is a rear elevational view thereof;

FIG. 4 is a right side elevational view thereof;

FIG. 5 is a left side elevational view thereof;

Fig. 6 is a top plan view thereof; and,

FIG. 7 is a bottom view thereof.

The broken lines in the figures depict portions of the cap for shaver blade that form no part of the claimed design.

The portions of the cap for shaver blade shown in broken lines are included for the purpose of illustrating unclaimed portions of the cap for shaver blade and form no part of the claimed design.
